UNITED STATES PATENT OFFICE.

JOHN A. TORRENS, OF COLERAINE, IRELAND.

INTERNAL-COMBUSTION ENGINE.

No. 893,400.

Specification of Letters Patent.

Patented July 14, 1908.

Application filed May 15, 1908. Serial No. 433,121.

To all whom it may concern:

Be it known that I, JOHN ARTHUR TORRENS, a subject of the King of Great Britain, residing at Somerset, Coleraine, in the county 5 of Londonderry, Ireland, have invented certain new and useful Improvements in Internal-Combustion Engines, of which the following is a specification.

This invention relates to four cycle internal combustion engines having automatically actuated inlet and exhaust valves controlled by a single mechanically operated valve situated between those valves and the cylinder of the engine, and consists in certain improvements in the construction and operation of such engines which have for their main object the production of a simple and efficient reversible single or multiple cylinder engine.

The present invention further consists in the construction wherein the controlling or main valve works in a valve chest integral with the side of the cylinder and the inlet and exhaust valves are mounted in a detachable 20 valve box bolted to the main valve chest and subdivided to form inlet and exhaust passages. At the beginning of the exhaust stroke the main valve is opened and remains open until the end of the suction stroke, the 25 spring urged exhaust and inlet valves in the meantime opening and closing automatically according to the conditions of pressure obtaining in the cylinder. During the compression and working strokes the main valve 30 remains closed. Such an arrangement of valves and cycle of operations have been previously used or proposed in internal combustion engines but in such engines the method of operating the main valve has precluded 35 any reversing of the engine. Since, according to the present invention, the operation of the main valve is symmetrical with respect to the engine cycle, being successively open and closed during two strokes for either direction of running of the engine, it is obvious 40 that with automatic inlet and exhaust valves the engine will work equally well in either direction.

The preferred arrangement of valves according to the present invention is illustrated 45 with respect to a two cylinder engine in the accompanying drawings, in which

Figure 1 is a part sectional elevation showing all the parts necessary for the understanding of the invention; Fig. 2 is a central 50 section at right angles to that of Fig. 1 of the

engine cylinder and main valve chest; Fig. 3 is a plan view of the inlet and exhaust valve box, and Fig. 4 a section thereof.

As therein shown the main valve chest *a* is 60 not in the customary way detachably connected with the engine cylinders, but is cast on the side of the same and integral therewith and the cast iron inlet and exhaust valve box *b* bolted on under the main valve chest by the two bolts *a'*, a copper gasket *b'* around the face of the seat of the inlet valve or of both inlet and exhaust valves insuring a tight joint where necessary between the two casings. This valve box is subdivided by a 65 partition *c* into two compartments *d*, *e*, in the former of which are two inlet valves *f* and in the latter the two exhaust valves *g*. The partition is arranged to lead the exhaust gases past the inlet valve compartment on 70 their passage to the exhaust pipe *h* so as to heat the casing where the air and oil spray from the carburetor, which may be conveniently placed immediately over the inlet passage *i*, enters the inlet valve box.

The spindle of the main valve *k* is guided in a tubular guide *j* screwed into or otherwise secured to the underside of the main valve chest *a* and extending downwardly through a recess *b* formed in the edge of the 80 valve box *b* for this purpose. The end of the guide *j* forms the fixed abutment for the returning spring *k'* of the valve. The valve spindle is actuated by means of a suitably guided and weighted or spring-urged tappet 85 *l* carrying a roller *l'* which bears on a cam *m* on the half time shaft *m*.

The main valve *k* acts in a known way in conjunction with the main valve chest *a*, which is unjacketed, to vaporize the charge 90 of fuel or heat the air at the last possible moment before entering the cylinder from said chest by way of the horizontal inlet *a*. The valve is designed to deflect the entering charge against the hot sides of the valve 95 chest, and the valve cover has a depending plug *a* which acts for the same purpose as additional storage of heat derived from the combustion products.

The inlet and exhaust valve spindles are 100 guided in plugs removably secured in the lower side of the valve box *b*, and the exhaust valve is preferably arranged so as to be able to open freely to a certain extent before the action of the returning spring comes into 110 play. This may be effected as shown by placing the returning spring *n* on a rod *n*

suitably guided in line with the valve spindle but with clearance enough between the adjacent ends to give the required amount of free opening to the valve.

- 5 It will be evident that by the construction herein described and illustrated pipes and pipe joints are practically entirely done away with, and that nevertheless all parts of the engine dealt with in the present invention 10 are readily accessible simply by slackening off the two bolts *a'* and breaking joint at the exhaust pipe so as to be able to remove the casting *b*.

Having thus described the nature of this 15 invention and the best means I know of carrying the same into practical effect, I claim:—

1. In internal combustion engines, in combination, an engine cylinder having a main valve chest at one side thereof and communicating therewith, a valve box detachably secured to said chest and having inlet and exhaust chambers communicating with said chest, a main valve controlling communication between said chest and the engine cylinder, inlet and exhaust valves controlling the communication between said chest and said valve box means acting to hold said several valves normally seated and

means for positively operating said main valve.

2. In internal combustion engines, in combination, an engine cylinder having a main valve chest at one side thereof and communicating therewith, a valve box detachably secured to said chest, a partition in said valve box dividing the same into inlet and exhaust chambers, the passage of the products of combustion through the latter heating the former and the explosive fuel passing therethrough, said inlet and exhaust chambers having communication with said valve chest, a main valve controlling communication between said chest and the engine cylinder, inlet and exhaust valves controlling the communication between said chest and said valve box means acting to hold said several valves normally seated and means for positively operating said main valve.

In testimony whereof I have signed my name to this specification in the presence of 50 two subscribing witnesses.

JOHN A. TORRENS.
